(57) **CLAIM**

The ornamental design for a pet toy as shown and described.

DESCRIPTION

FIG. 1 is a perspective view of a first embodiment of a pet toy showing the new design.

FIG. 2 is a top view thereof; the bottom view being a mirror image thereto.

FIG. 3 is a front view thereof.

FIG. 4 is a right side view thereof; the left side view being a mirror thereto.

FIG. 5 is a rear view thereof.

FIG. 6 is a perspective view of a second pet toy embodiment.

FIG. 7 is a top view thereof; the bottom view being identical thereto.

FIG. 8 is a front view thereof, the left and right side views being identical thereto.

FIG. 9 is another side view thereof, taken from the front-right position.

FIG. 10 is a perspective view of a third pet toy embodiment.

FIG. 11 is a top view thereof; the bottom view being a mirror image thereto.

FIG. 12 is a front view thereof.

FIG. 13 is a right side view thereof; the left side view being a mirror image thereto.

FIG. 14 is a rear view thereof.

FIG. 15 is a perspective view of a fourth pet toy embodiment.

FIG. 16 is a top view thereof; the bottom view being identical thereto.

FIG. 17 is a front view thereof; the rear view being identical thereto.

FIG. 18 is a right side view thereof; the left side view being a mirror image thereto.

FIG. 19 is an enlarged detail view of portion 19 shown in FIG. 8; and,

FIG. 20 is an alternate configuration view of FIG. 19 shown in a flexed position.

(Continued)

The broken lines in the drawings represent boundaries of enlarged views and form no part of the claimed design.

1 Claim, 19 Drawing Sheets
